D. STOLL

METAL STRIP OR SIMILAR ARTICLE OF MANUFACTURE

Filed March 14, 1923

A B Inventor.

David Stoll

BY Harry J. Stoll

UNITED STATES PATENT OFFICE.

DAVID STOLL, OF NEW YORK, N. Y.

DESIGN FOR A METAL STRIP OR SIMILAR ARTICLE OF MANUFACTURE.

Application filed March 14, 1923. Serial No. 5,470. Term of patent 3½ years.

To all whom it may concern:

Be it known that I, DAVID STOLL, a citizen of the United States, and resident of the city of New York, in the county of Kings and State of New York, have invented a new, original, and ornamental Design for Metal Strip or Similar Article of Manufacture, of which the following is a specification, reference being had to the accompanying drawing, forming part thereof.

The figure is a top plan view of a metal strip, to which my new design has been applied, the left portion of the figure being intended to be made continuous with that portion shown on the right by arranging said portions with the lines A—B thereof coincident.

The design appears largely in rilievo and partly in intaglio on the wide surface of the strip.

It is intended that metal strip embodying my new design be attached to other articles, as for example, articles of silver hollow ware, for forming an ornamental band or border on said articles.

I claim:

The ornamental design for a metal strip or similar article of manufacture as shown and described.

Signed at the city of New York, in the county of New York and State of New York, this 13th day of March, 1923.

DAVID STOLL.
